[57] CLAIM

The ornamental design for an infant's bathtub, substantially as shown and described.

DESCRIPTION

FIG. 1 is a perspective view of an infant's bathtub showing my new design;

FIG. 2 is a top plan view of the tub portion thereof;

FIG. 3 is a top plan view of the infant holding portion thereof;

FIG. 4 is a side elevational view of FIG. 3; and

FIG. 5 is a left end elevational view of FIG. 1.
